INSTITUTIONAL FOOD SERVER

E. Burton Benjamin, Highland Park, and Richard Sylvan, Glenview, Ill., assignors to Carter-Hoffmann Corp.

Filed Jan. 30, 1970, Ser. No. 21,162

Term of patent 14 years

Int. Cl. D12—02

U.S. Cl. D14—6

FIG. 1 is a perspective view of an institutional food server embodying the design of our invention;

FIG. 2 is a perspective view of the institutional food server shown in FIG. 1, taken from the opposite side thereof; and

FIG. 3 is a side elevational view of the institutional food server shown in FIG. 1.

We claim:

The ornamental design for an institutional food server, as shown.
